(57) **CLAIM**

The ornamental design for an electric connector, as shown and described.

DESCRIPTION

FIG. 1 is a front elevational view of an electric connector showing my new design;

FIG. 2 is a top plan view thereof;

FIG. 3 is a rear elevational view thereof;

FIG. 4 is a bottom plan view thereof;

FIG. 5 is a right side elevational view thereof;

FIG. 6 is a front, top, and left side perspective view thereof;

FIG. 7 is a rear, top, and left side perspective view thereof; and,

FIG. 8 a front, top, and left side perspective view thereof, in a use condition.

The broken lines in the drawings depict environmental subject matter only and form no part of the claimed design.
